UNITED STATES PATENT OFFICE

EDWIN W. SEEGER, OF SOUTH MILWAUKEE, WISCONSIN, ASSIGNOR, BY MESNE ASSIGNMENTS, TO CUTLER-HAMMER INC., OF MILWAUKEE, WISCONSIN, A CORPORATION OF DELAWARE

PUSH-BUTTON ELEVATOR-CONTROL SYSTEM

Application filed October 27, 1926. Serial No. 144,415.

This invention relates to push button elevator control systems.

An object of the invention is to provide improved and simplified selector mechanism providing for accurate positioning of the car in stopping at any desired preselected landing.

Another object is to provide selector mechanism of the above character adapted to control the speed of the driving motor during automatic initiation of the stopping operation of the latter.

Another and more specific object of the invention is to provide improved selector mechanism adapted to insure slow speed operation of the driving motor at a predetermined point in the travel of the car, together with cooperating means in the hoistway and on the car for effecting accurately positioned stopping of the latter at a preselected landing.

Another object is to minimize the number of car operated switches required and to avoid the noise and wear incident to unnecessary operation of the latter.

Another object is to provide selector mechanism operable in a direction and to a degree corresponding with the movement of the car, with means for automatically adjusting the selector at the upper and lower limits of travel of the car, if necessary.

Another object is to generally improve the construction and operation of control systems of the character aforementioned.

Other objects and advantages of the invention will hereinafter appear.

The accompanying drawing illustrates one embodiment of the invention which will now be described, it being understood that various changes may be made in the details of construction and operation of the system without departing from the spirit and scope of my invention as defined in the appended claims.

In the drawing, Figure 1 illustrates schematically and diagrammatically a control system constructed in accordance with my invention;

Fig. 2 is an across-the-line diagram of the circuits and circuit connections illustrated in Fig. 1; and

Fig. 3 is a diagrammatic view of my improved form of selector drive and adjuster.

Referring first to Fig. 1, M designates a motor adapted to drive the elevator car (not shown) through any suitable or well known connection. As shown, the direction of operation of motor M is controlled through suitable reversing switches U and D, operation of the latter being controllable respectively by means of relays UR and DR, subject, however, to control by a retiring limit switch RS. Motor M is provided with a low speed winding (the terminals of which are indicated at T¹¹, T¹² and T¹³) energization of which is controlled by switch S, and a high speed winding (the terminals of which are indicated at T¹, T² and T³) energization of which is controlled by switch F; suitable relays SDR and SAR being provided to change from low to high speed connections, and vice versa, under given conditions as hereinafter described. Acceleration under low speed conditions is controlled by exclusion of resistances R¹ and R² through operation of switch ACS in the manner hereinafter described, resistances R³, R⁴ and R⁵ being adapted for permanent inclusion in circuit with the low speed winding.

Relay SDR is in turn subjected to control by relay FAR, the latter being also adapted to thereafter effect operation of accelerating switches ACF¹ and ACF² in sequence, to exclude resistances R⁶, R⁷ and R⁸, R⁹, respectively, from the circuit of the high speed winding.

A brake releasing coil BR and the winding of a non-interference relay NIR for control of the various push buttons are arranged to be connected across lines L¹, L³, upon closure of switch U or switch D.

I have illustrated my invention as applied to control of an elevator having four floors or landings, but it is to be understood that the same is likewise applicable to control of elevators having a greater or lesser number of landings. Thus I have provided landing relays LR¹, LR², LR³ and LR⁴, corresponding to the first to fourth landings, respectively. Initial energization of the respective relays

- is controlled by push button switches LP^1 , LP^2 , LP^3 and LP^4 located at the several landings, or by corresponding push-buttons CP^1 , CP^2 , CP^3 and CP^4 located within the car.
- 5 Operation of the controller is dependent upon closure of all of the landing door switches LD^1 , LD^2 , LD^3 and LD^4 , as will be obvious. Certain of the aforementioned relays and switches are provided with normally open or
- 10 normally closed auxiliary contacts, or both, which function in the manner hereinafter set forth.
- Operation of the control system will now be described with more particular reference
- 15 to the across-the-line diagram of Fig. 2. Thus with the car at the second landing, as indicated in the drawing by the position of selector switch LS , and assuming that it is desired to call the car to the fourth landing,
- 20 the push button LP^4 at the fourth landing may be depressed, thereby completing a common energizing circuit for the windings of relays LR^4 and UR , respectively. Said circuit may be traced from line L^3 through contacts 10 of overtravel limit switch OT and contacts 11 of overtravel limit switch OT^1 , thence by conductors 75, 76 and 31 through normally closed auxiliary contacts 12 of relay DR and normally closed auxiliary contacts 13 of relay UR and through the normally closed upper contacts of push button switches CP^1 , CP^2 , CP^3 and CP^4 , thence through the normally closed contacts 14 of non-interference relay NIR and through
- 35 the normally open lower contacts of push button switch LP^4 , thence through the winding of relay LR^4 to contact 15 of selector switch LS to segment 16 and contact 17 of the latter, through the winding of relay UR by conductors 77 and 78 to and through the normally closed contacts of the emergency "stop" switch located within the car, thence through the contacts of car door switch CDS (assuming closure of the car door) and the
- 40 contacts 18 of overtravel limit switch OT^1 , thence through the contacts of the landing door switches LD^1 , LD^2 , LD^3 and LD^4 , respectively, and through contacts 19 of overtravel limit switch OT to line L^1 .
- 45 As illustrated in Fig. 1 cams HC^1 , HC^2 , HC^3 and HC^4 are provided in the hoistway adjacent to the first to fourth landings, respectively; whereas with the car at the second landing and the winding 20 of retiring switch RS deenergized the contacts 21 of said switch will be separated through engagement of roller 22 with cam HC^2 . However, upon closure of relay UR the contacts 23 thereof are
- 50 adapted to complete an energizing circuit for the winding 20, thus permitting normally closed positioning of contacts 21, said circuit extending from line L^3 through contacts 10 and 11 as aforescribed, thence by conductors 75 and 24 through contacts 23, by conductor
- 55 through winding 20 by conductors 26 and 27 to contacts 18 and thence to line L^1 as heretofore traced.
- 60 Contacts 28 of relay UR being also closed an energizing circuit is provided for the winding of switch U upon closure of the aforementioned contacts 21 of switch RS . Said circuit may be traced from line L^3 to conductors 75 and 76 as aforescribed, thence through contacts 28, by conductors 29 and 79 through the winding of switch U , through the contacts of limit switches TU and CU and the contacts 21 of switch RS , thence by conductors 80 and 78 through the emergency "stop" push button switch, and to line L^1 as heretofore traced. Upon closure of switch U a maintaining circuit is provided therefor through closure of its auxiliary contacts 30, in shunt with the contacts 28 of relay UR .
- 65 Upon energization of the relay LR^4 in the manner aforescribed a maintaining circuit is provided therefor which is independent of the various push button control switches, said circuit extending from line L^3 through contacts 10 and 11, thence by conductors 75, 76, 31, 32 and 33 through the contacts of said relay LR^4 and through the winding thereof to line L^1 as heretofore traced. Thus upon closure of relay UR the normally closed auxiliary contacts 13 thereof are opened to disconnect the push button switches from the line, but the energizing circuits of relays LR^4 and UR will be maintained as aforescribed.
- 70 Under the aforescribed conditions an energizing circuit is provided for the winding of low speed switch S , said circuit extending from line L^3 through contacts 10 and 11, by conductors 75, 24, 52, and 81 through the winding of switch S , thence by conductor 82 through normally closed auxiliary contacts 36 of relay SDR , or alternatively through normally closed auxiliary contacts 37^a, 37 and 37^b of high speed switch F by conductor 83 to conductor 27, and thence through contacts 18 to line L^1 as heretofore traced.
- 75 Thus upon closure of switches U and S as aforescribed the low speed windings of motor M will be energized through circuits extending from line L^1 by conductors 84 and 85 through one set of contacts of switch U thence by conductor 86 through contacts S^1 of switch S and through resistances R^1 and R^3 to terminal T^{11} ; also from line L^2 by conductors 87 and 88 through contacts S^2 of switch S and through resistances R^2 and R^4 to terminal T^{12} ; and from line L^3 by conductors 89 through the other set of contacts of switch U and by conductors 42 and 90 through resistance R^5 to terminal T^{13} .
- 80 Also upon closure of switch U an energizing circuit is provided for the winding of accelerating relay ACS , said circuit extending from line L^1 by conductors 84 and 85

through the first-mentioned set of contacts of switch U, by conductors 38 and 39 through said winding and the normally closed contacts 40 of relay SAR, and by conductors 41 and 42 through the other set of contacts of switch U by conductor 89 to line L³. Switch ACS thereupon closes to short-circuit resistances R¹ and R², thereby increasing the speed of the motor.

10 Also upon closure of relay UR and switch U, an energizing circuit is provided for the winding of relay FAR, said circuit extending from line L³ to conductors 75 and 24, thence through the contacts 23 of relay UR and by conductor 91 through auxiliary contacts 43 of switch U, through the winding of relay FAR and through normally closed auxiliary contacts 37^a, 37 and 37^b to conductors 83 and 27, and thence to line L¹ as previously traced. The pivoted contactor 44 of relay FAR is thereupon moved upwardly into engagement with contact 45, thereby completing an energizing circuit for the winding of relay SDR, said circuit extending from line L³ to and through the auxiliary contacts 43 of relay U, thence by conductors 92, 46 and 47 through the winding of relay SDR, by conductors 48 and 49 through contactor 44 and contact 45, and by conductors 93, 26 and 27 to line L¹ as previously traced. Relay SDR in closing provides a maintaining circuit for itself through its contacts 50 shunting contactor 44 and contact 45 of relay FAR.

15 Relay SDR in closing also completes an energizing circuit, through its contacts 51, for the winding of switch F; said circuit extending from line L³ to conductors 75 and 24, thence by conductor 52 through said winding, by conductor 53 through said contacts 51, and thence to conductors 26 and 27 and line L¹ as heretofore traced. Switch F in closing effects opening of its normally closed auxiliary contacts 37, 37^a, 37^b and 37^c, thereby interrupting the energizing circuit of relay FAR and the alternative energizing circuit of switch S, the other energizing circuit of switch S having been likewise interrupted through opening of normally closed auxiliary contacts 36 of relay SDR. Switch S having been opened and switch F closed in the manner just described, an alternative maintaining circuit is provided for the latter through closure of its normally open auxiliary contacts F³ and reclosure of the normally closed auxiliary contacts S³ of switch S.

20 The main contacts F¹ and F² of switch F being thus closed, motor M is connected to the line through its high speed windings, the circuits thereof extending from line L¹ by conductors 84 and 85 through one set of contacts of switch U, thence by conductors 38 and 86 through contacts F¹ through resistances R⁶ and R⁸ to terminal T¹; also from line L² by conductors 87 and 94 through contacts F²

and resistances R⁷ and R⁹ to terminal T²; and from line L³ by conductor 89 through the other set of contacts of switch U and by conductors 42 and 90 to terminal T³.

25 Relay FAR having been deenergized as aforescribed, contactor 44 thereof tends to move by gravity to the position illustrated in Figs. 1 and 2 wherein it engages contacts 54 and 55, contact 54 being of greater length than contact 55 whereby said contacts are engaged sequentially. However, relay FAR is provided with a down-dashing dashpot 56 for retarding the reclosing movement of contactor 44 with respect to contacts 54 and 55. Thus, with contacts 50 of relay SDR closed as aforescribed, reclosure of contactor 44 and contact 54 provides an energizing circuit for the winding of accelerating switch ACF¹, which circuit may be traced from line L³ to conductor 46 as aforescribed, thence by conductor 57 through said winding, thence through contact 54 and contactor 44 by conductor 49 through contacts 50 of relay SDR, and thence by conductors 26 and 27 to L¹ as heretofore traced. The contacts of switch ACF¹ thereupon close to short-circuit resistances R⁶ and R⁷. Thereafter contactor 44 comes into engagement with contact 55 thus completing an energizing circuit for the winding of switch ACF², which circuit may be traced from line L³ to conductor 46, through said winding, thence through contact 55 and contactor 44 to conductor 49 and contacts 50 of relay SDR, and thence to conductors 26 and 27 to line L¹. The contacts of switch ACF² thereupon close to short-circuit resistances R⁸ and R⁹, thereby connecting the high speed winding of motor M directly across the line.

30 In the manner aforescribed motor M is started and accelerated to full speed operation thereof. Also during movement of the car from the second landing toward the fourth landing under the aforementioned conditions the landing selector switch LS is moved to a proportional degree.

35 In Fig. 3 I have diagrammatically illustrated one form of driving connection for the landing selector switch LS. Said connection as shown comprises a relatively small pulley 58 secured to the motor shaft 59 and a relatively large pulley 60 secured to a shaft 61 carrying the selector LS. Pulleys 58 and 60 are so proportioned as to provide the necessary reduction in speed and the same are connected by a belt 62. Thus upon operation of motor M in a direction to effect upward movement of the car, selector LS is driven at a proportional speed in a clockwise direction, as indicated by the arrow, Figs. 1 to 3.

40 Selector LS as shown must be limited to clockwise and counterclockwise movement through an arc of 180 degrees, and I therefore provide means for automatically adjusting the position of the selector, if necessary, at the

respective up and down limits of travel of the car. Said means may comprise a pin or other projection 63 on pulley 60 and a pair of opposed abutments 64 and 65 arranged in the 5 path of said pin. Thus upon movement of the car to the fourth landing selector LS is permitted to move in a clockwise direction to a position wherein segment 16 is disengaged from contact 15, but no farther, due to engagement of pin 63 with abutment 64; any 10 tendency to drive selector LS farther being compensated for by slippage of belt 62 on pulley 60, thus obviating the necessity for employment of a slip-clutch in the drive. 15 Similarly upon downward movement of the car toward the first landing, counterclockwise movement of selector LS is permitted until pin 63 engages abutment 65, whereas any tendency to drive the selector farther in 20 such direction is compensated for by slippage of belt 62 on pulley 60 as aforescribed.

It may be pointed out here that finely calibrated adjustment of selector LS is unnecessary, and hence any slight inaccuracy or misalignment of the selector during oscillation thereof between its respective limits will not affect the operation of the system as a whole.

Thus with motor M brought to full speed in the manner aforescribed, and after the car 30 has moved upwardly past the third landing, but prior to arrival thereof at the fourth landing, segment 16 of selector LS is adapted to move out of engagement with contact 15, thereby interrupting the common energizing circuit 35 of the windings of relays LR⁴ and UR. Upon deenergization of relay UR the contacts 28 thereof will be opened, thus tending to interrupt the energizing circuit of the winding of switch U. The energizing circuit of 40 switch U is maintained, however, through closure of its auxiliary contacts 30 as aforescribed. Contacts 23 of relay UR will also be opened, thereby interrupting the energizing circuit of the winding 20 of retiring switch 45 RS. Said switch will thereupon be permitted to oscillate on its pivot 66 to a position wherein the cam HC⁴ will be in the path of roller 22, but the contacts 21 of said switch will be maintained closed through the action of 50 spring 67.

Also upon opening of contacts 23 of relay UR the energizing circuits of relays ACF², ACF¹ and SDR will be interrupted, as will be obvious. Thereupon resistances R⁶ to R⁹ will 55 be reincorporated in circuit with the high speed windings of motor M, thus reducing the speed of the latter. Moreover, upon deenergization of relay SDR the auxiliary contacts 36 thereof will be reclosed, thereby completing the 60 aforescribed energizing circuit for the winding of low speed switch S. Contacts 51 of relay SDR in opening interrupt one of the maintaining circuits for switch F, the alternative maintaining circuit of said switch being 65 also interrupted immediately upon clo-

sure of switch S, through opening of the auxiliary contacts S⁸ of the latter.

With switch F thus opened and switch S closed motor M will be brought to low speed, whereas upon arrival of the car at a predetermined point adjacent to the fourth landing roller 22 on the switch RS attached to the car will come into engagement with cam HC⁴, thereby opening the contacts 21 of said switch to effect interruption of the energizing circuit of switch U. Upon opening of the contacts of switch U the energizing circuit of brake coil BR is interrupted whereby the brake is released and the motor stopped with the car accurately positioned at said landing.

By employment of a retiring switch of the character herein disclosed I obviate the usual noise incident to operation of one or more switches during movement of the car past the several landings. Moreover, by the arrangement described the amount of wear on the operating parts of the selector mechanism is minimized.

Referring again to Fig. 1, it will be noted that I have provided normally closed limit switches CU and TU which are located at spaced points in the hoistway adjacent to the upper landing but below the "up" overtravel limit switch OT; whereas similar limit switches CD and TD are located at spaced points in the hoistway adjacent to the lower landing but above the "down" overtravel limit switch OT¹. Thus as illustrated more clearly in Fig. 2 the car may normally move upwardly to a position wherein limit switch CU is opened without interrupting the energizing circuit of switch U, provided the reduction in speed of the motor is being accomplished by closure of the low speed switch S, which results in closure of the normally open auxiliary contacts S⁴ of the latter. A shunt around the contacts of limit switch CU is thus provided, which may be traced from the contacts of limit switch TU through said auxiliary contacts S⁴, and through the contacts of limit switch CD to and through contacts 21 of retiring switch RS. If the car should effect opening of both limit switches TU and CU prior to closure of low speed switch S the energizing circuit of switch U will be interrupted immediately to effect stopping of the motor and consequently of the car, as aforescribed. The operation of limit switches CD and TD during movement of the car to the first landing is in all respects like that of limit switches CU and TU as just described, and hence further description thereof is deemed unnecessary. The function of limit switches OT and OT¹ is well understood by those skilled in the art, and further description thereof is deemed unnecessary.

The operation of relay NIR is also well understood, and the same forms no part of

the present invention. Similarly the arrangement of the electrical interlocks between the various push button switches per se forms no part of the present invention.

It is thought that the operation of the control system in all other respects will be obvious from the foregoing. It may be noted, however, that upon completion of an operation, such as that described in connection with movement of the car from the second landing with accurate stopping thereof at the fourth landing, all parts of the system are automatically reset for further automatic operation upon depression of one of the push button switches. Thus assuming the car to have arrived at the fourth landing and further assuming that the person who called the car has opened the landing door LD⁴ and the car door CDS and has entered the car and re-closed said doors. The car may then be directed to any of the other landings by temporarily depressing the proper push button CP¹, CP² or CP³. Assuming depression of push button CP¹, a common energizing circuit will be provided for relays LR¹ and DR, which circuit extends from line L³ to and through contacts 10 and 11 of switches OT and OT¹ and by conductors 75, 76 and 31 through auxiliary contacts 12 and 13 of relays DR and UR, through lower contacts of push button switch CP¹, thence through the winding of relay LR¹ to and through contact 68, segment 69 and contact 70 of selector LS, thence through the winding of relay DR and to line L¹, as previously traced. Thereupon switch D is energized and closed to initiate operation of motor M as aforescribed, but in a reserve direction. The accelerating and slowing down operations of motor M are substantially as aforescribed, and hence more specific description thereof is deemed unnecessary. It may be noted that selector LS is provided with a contact 71 for cooperation with segments 69 or 16, as the case may be, during calling or directing of the car to the second landing; whereas said selector LS is likewise provided with a contact 72 for cooperation with segments 69 or 16 during calling or directing of the car to the third landing.

The normally open auxiliary contacts 73 and 74 of switch D correspond with normally open auxiliary contacts 30 and 43 of switch U and function in a like manner.

As aforeindicated, relay FAR is provided with a down-dashing dashpot to retard the reclosing movement of contactor 44 with respect to contacts 54 and 55; whereas relays SAR and NIR are similarly provided with down-dashing dashpots to retard the reclosing movement of their respective contacts 40 and 14, as aforescribed.

While I have specifically illustrated my invention as applied to the control of a variable speed motor, it will be apparent to

those skilled in the art that certain features thereof may be applied with equal facility to the control of a single speed motor.

What I claim as new and desire to secure by Letters Patent is:

1. In a push button elevator control system, the combination with a variable speed reversible motor for driving the car, of a plurality of push button switches operable selectively to initiate operation of the motor, means comprising a selector switch cooperating with said push button switches to pre-determine the direction and the approximate duration of operation of said motor, and means also controlled by said selector switch comprising a retiring switch carried by the car and a cam in the hoistway, said retiring switch being releasable by said selector switch to insure engagement thereof with said cam during approach of the car to a preselected landing, whereby said motor is stopped only when the car is accurately positioned at said landing, said selector switch being also operable to insure low speed circuit connections for said motor prior to arrival of the car at said landing.

2. In a push button elevator control system, the combination with a car, of a variable speed reversible motor for driving the same, a plurality of push button switches within the car and at the respective landings for selectively initiating operation of the motor, means comprising a selector switch for controlling the direction of operation of said motor, a normally closed limit switch carried by the car and cams in the hoistway adjacent to the respective landings tending to effect opening of said limit switch, and means controlled by said selector switch for retiring said limit switch pending approach of the car to a point adjacent to a preselected landing, said selector switch thereupon acting to insure release of said limit switch for engagement of the latter with a cam in the hoistway adjacent to said landing, whereby said motor is stopped only when said car is accurately positioned at said landing, said selector switch also acting to insure low speed circuit connections for the motor prior to said stopping thereof.

3. In a push button elevator control system, the combination with a car, of a variable speed driving motor therefor, means including a plurality of push button switches for selectively initiating operation of said motor for effecting travel of said car to a preselected point, said means also comprising a selector device operable to insure low speed connections for the motor during approach of the car to said point and prior to stopping of the motor, and cooperating means adjacent to said point and on the car to insure accurately positioned stopping of the latter in the first instance through interruption of said low speed connections.

4. In a push button elevator control system the combination with a car, of a variable speed reversible motor for driving same, means including a plurality of push button switches for selectively initiating operation of the motor to effect movement of the car toward a preselected point, said means including selector mechanism to control the direction of operation of the motor, said mechanism being also adapted to insure predetermined reduced speed conditions of the motor without interruption of the power supply thereof at a given point in the travel of the car during approach of the latter to said preselected point, and cooperating means adjacent to said preselected point and on said car for effecting interruption of said power supply to insure accurately positioned stopping of the car at said pre-selected point. 70
5. In a selector mechanism for push button elevator control systems, the combination with a motor for driving the car, of an element having movement proportional to the movement of the car, means including a plurality of push button switches and said element for preselecting the landing at which the car is to be stopped, said element acting automatically when the car is approaching and adjacent to said landing to vary the speed of said motor without interrupting the power supply thereof, and means comprising cooperating elements on the car and in the hoist-way to insure accurately positioned stopping of the car at said preselected landing. 75
6. In selector mechanism for push button elevator control systems, the combination with a motor for driving the car, of an element having movement proportional to the movement of the car, means including a plurality of push button switches and said element for preselecting the landing at which the car is to be stopped, said element acting automatically during approach of the car to said landing to vary the speed of said motor while maintaining the same direction of power operation of the latter, and means comprising a cam in the hoistway and a cooperating switch on the car to initiate and effect stopping of the motor when the car is accurately positioned at said landing. 80
7. In an elevator control system, the combination with a car, of a variable speed reversible motor for driving same, a plurality of push button switches operable selectively to effect operation of said motor, means operable in a direction and to a degree corresponding with the movement of said car and cooperating with said push button switches to preselect and control the direction and approximate duration of operation of said motor, means controlled by said last mentioned means and operable automatically during approach of the car to a preselected landing to insure a predetermined reduction in speed of said motor as an initial step in the stopping operation of the latter, and means for initially stopping said motor from low speed with the car accurately positioned at said landing. 85
8. In an elevator control system, the combination with a car, of a variable speed reversible motor for driving the same, an electromagnetically operable brake for said motor, a plurality of push button switches located within the car and at the respective landings, means cooperating with the respective push button switches for initiating operation of said motor and for selectively controlling the direction and approximate duration of operation thereof, said means being also operable to automatically accelerate said motor during movement of the car in a given direction toward a preselected landing and for thereafter insuring predetermined low speed circuit connections for said motor prior to arrival of the car at said landing, and means carried by the car and operable upon movement of the latter in said given direction to a predetermined point with respect to said landing to immediately effect interruption of the power connections of said motor and application of said brake to insure accurately positioned stopping of the car at said landing in the first instance. 90
9. In an elevator control system, the combination with a car, of a variable speed reversible motor for driving the same, a plurality of push button switches located within the car and at the respective landings, means cooperating with the respective push button switches for initiating operation of said motor and for selectively controlling the direction and approximate duration of operation thereof, said means being also operable to automatically accelerate said motor pending movement of the car in a given direction to a point adjacent to a preselected landing and for thereafter insuring predetermined low speed circuit connections for said motor prior to arrival of the car at said landing, and means carried by the car and operable upon movement of the latter in said given direction to a predetermined point with respect to said landing to immediately interrupt operation of said motor to insure accurately positioned stopping of the car at said landing in the first instance. 95
10. In a push button elevator control system, the combination with a car, of a variable speed motor for driving the same in reverse directions selectively, a plurality of push button switches located within the car and at the respective landings and operable selectively to initiate operation of the motor, means comprising a selector driven by said motor and cooperable with the respective push button switches to preselect the direction and approximate duration of travel of said car, said selector being also operable automatically. 100
11. In a selector mechanism for push button elevator control systems, the combination with a motor for driving the car, of an element having movement proportional to the movement of the car, means including a plurality of push button switches and said element for preselecting the landing at which the car is to be stopped, said element acting automatically when the car is approaching and adjacent to said landing to vary the speed of said motor without interrupting the power supply thereof, and means comprising cooperating elements on the car and in the hoist-way to insure accurately positioned stopping of the car at said preselected landing. 105
12. In a selector mechanism for push button elevator control systems, the combination with a motor for driving the car, of an element having movement proportional to the movement of the car, means including a plurality of push button switches and said element for preselecting the landing at which the car is to be stopped, said element acting automatically during approach of the car to said landing to vary the speed of said motor while maintaining the same direction of power operation of the latter, and means comprising a cam in the hoistway and a cooperating switch on the car to initiate and effect stopping of the motor when the car is accurately positioned at said landing. 110
13. In an elevator control system, the combination with a car, of a variable speed reversible motor for driving the same, a plurality of push button switches operable selectively to effect operation of said motor, means operable in a direction and to a degree corresponding with the movement of said car and cooperating with said push button switches to preselect and control the direction and approximate duration of operation of said motor, means controlled by said last mentioned means and operable automatically during approach of the car to a preselected landing to insure a predetermined reduction in speed of said motor as an initial step in the stopping operation of the latter, and means for initially stopping said motor from low speed with the car accurately positioned at said landing. 115
14. In an elevator control system, the combination with a car, of a variable speed reversible motor for driving the same, an electromagnetically operable brake for said motor, a plurality of push button switches located within the car and at the respective landings, means cooperating with the respective push button switches for initiating operation of said motor and for selectively controlling the direction and approximate duration of operation thereof, said means being also operable to automatically accelerate said motor during movement of the car in a given direction toward a preselected landing and for thereafter insuring predetermined low speed circuit connections for said motor prior to arrival of the car at said landing, and means carried by the car and operable upon movement of the latter in said given direction to a predetermined point with respect to said landing to immediately effect interruption of the power connections of said motor and application of said brake to insure accurately positioned stopping of the car at said landing in the first instance. 120
15. In a selector mechanism for push button elevator control systems, the combination with a motor for driving the car, of an element having movement proportional to the movement of the car, means including a plurality of push button switches and said element for preselecting the landing at which the car is to be stopped, said element acting automatically when the car is approaching and adjacent to said landing to vary the speed of said motor without interrupting the power supply thereof, and means comprising cooperating elements on the car and in the hoist-way to insure accurately positioned stopping of the car at said preselected landing. 125
16. In a selector mechanism for push button elevator control systems, the combination with a motor for driving the car, of an element having movement proportional to the movement of the car, means including a plurality of push button switches and said element for preselecting the landing at which the car is to be stopped, said element acting automatically during approach of the car to said landing to vary the speed of said motor while maintaining the same direction of power operation of the latter, and means comprising a cam in the hoistway and a cooperating switch on the car to initiate and effect stopping of the motor when the car is accurately positioned at said landing. 130

- cally to reduce the speed of said motor while maintaining the power connections thereof during approach of the car to a preselected landing, and a retiring switch carried by said car and controllable by said selector during approach of the car to said landing for automatic movement into a position to engage a cam adjacent to said landing to thereby provide for accurately positioned immediate 5 stopping of the car with respect to said landing in the first instance under said reduced speed conditions of the motor.
11. In a push button elevator control system, the combination with a car, of a reversible motor for driving said car, speed controlling means for said motor including low speed and high speed connections therefor, a plurality of push button switches within the car and at the respective landings, means 15 cooperating with the respective push button switches for controlling the direction of operation of said motor and for automatically commutating the low speed and high speed connections of the latter, said means comprising a selector switch driven by said motor at a speed proportional to the speed of said car, a normally closed limit switch carried by the car and cams in the hoistway adjacent to the respective landings tending to open 20 said switch, electromagnetic means controlled by said selector switch for normally retiring said limit switch and operable to insure release of the latter upon movement of the car to a point intermediate a preselected landing and the next preceding landing, and means controlled simultaneously by said selector switch to insure low speed connections for said motor, said limit switch being thereafter opened by a cam prior to arrival 25 of the car at said preselected landing to immediately effect accurately positioned stopping of the car at said landing in the first instance.
12. In a push button elevator control system, the combination with a car, of a reversible motor for driving said car, speed controlling means for said motor including low speed and high speed connections therefor, a plurality of push button switches within 30 the car and at the respective landings, means cooperating with the respective push button switches for controlling the direction of operation of said motor and for commutating the low speed and high speed connections, 35 said means comprising a selector switch driven by said motor at a speed proportional to the speed of said car, a normally closed limit switch carried by the car and cams in the hoistway adjacent to the respective landings tending to open said switch, and electromagnetic means controlled by said selector switch for retiring said limit switch pending movement of the car to a point intermediate a preselected landing and the next preceding landing, whereupon said limit switch is 40 opened by the cam adjacent to said preselected landing to effect accurate stopping of the car, said selector switch being operable to insure interruption of said high speed connections and establishment of said low speed 45 connections prior to stopping of said car.
13. In a push button elevator control system, the combination with a car, of a reversible motor for driving said car, speed controlling means for said motor including low speed and high speed connections therefor, a plurality of push button switches within the car and at the respective landings, means cooperating with the respective push button switches for controlling the direction of operation of 50 said motor and for commutating said low speed and high connections, said means comprising a selector switch having an automatically adjustable connection with said motor for driving of the former at a speed proportional to the speed of said car, a normally closed limit switch carried by the car and cams in the hoistway adjacent to the respective landings tending to open said switch, and electromagnetic means controlled by said selector switch for normally retiring said limit switch and operable to release the latter during approach of the car to a point intermediate a preselected landing and the next preceding landing, whereupon said limit switch is opened by the cam adjacent to said preselected landing to effect accurately positioned stopping of the car.
14. In a push button elevator control system, the combination with a reversible motor having low speed and high speed connections, of a car to be driven thereby, a selector switch and a belt and pulley connection between said motor and said switch for driving the latter at a speed proportional to and in a direction corresponding with the direction of movement of said car, said switch being operable automatically to commutate said low speed and high speed connections during approach of the car to a predetermined landing, and means for positively limiting the degree of movement of said selector switch in opposite directions to thereby provide for automatic adjustment of the latter at each limit of travel of the car.
15. In a push button elevator control system, the combination with a variable speed reversible motor, of a car to be driven thereby, a plurality of push button switches within the car and at the respective landings, a selector switch and an automatically adjustable connection between said motor and said switch for driving the latter at a speed proportional to and in a direction corresponding with the direction of movement of said car, said selector switch being adapted to cooperate with the respective push button switches for preselecting the direction and approximate duration of operation of said motor, means controlled by said selector

switch to insure a predetermined reduced speed of said motor prior to arrival of said car at a predetermined landing, and means comprising a switch on said car and a cam adjacent to said landing for insuring accurately positioned stopping of the car at said landing under said reduced speed conditions.

16. In a push button elevator control system, the combination with a variable speed reversible motor, of a car to be driven thereby, a plurality of push button switches within the car and at the respective landings, a selector switch and an automatically adjustable connection between said motor and said switch for driving the latter at a speed proportional to and in a direction corresponding with the direction of movement of said car, said selector switch being adapted to cooperate with the respective push button switches for preselecting the direction and approximate duration of operation of said motor, means controlled by said selector switch to insure a predetermined reduced speed of said motor prior to arrival of said car at a preselected landing, and means comprising a switch on said car and a cam adjacent to said landing for insuring accurately positioned stopping of the car at said landing under said reduced speed conditions, said last mentioned switch being normally closed and having electromagnetically operable means for moving and holding the same bodily out of alignment with said cam pending a given operation of said selector switch prior to arrival of the car at said landing.

17. In a push button elevator control system, the combination with a car, of a reversible motor for driving the same, a plurality of push button switches and an oscillatory selector switch cooperating therewith to control the direction of travel and destination of said car, said selector switch comprising a pair of conducting segments and contacts to be sequentially engaged therewith or disengaged therefrom, a belt and pulley connection between the motor and said selector switch to vary the position of the latter in accordance with variations in the position of the car, and means for positively limiting the degree of oscillatory movement of said selector switch to provide for automatic adjustment thereof in accordance with the position of the car.

18. In a push button elevator control system, the combination with a reversible motor, low speed and high speed windings therefor, resistances to be included in or excluded from the circuits of said windings respectively and means for commutating said resistances, a plurality of push button switches located within the car and at the respective landings, means for preselecting the direction of movement and destination of the car, said means comprising relays for controlling the forward or reverse operation of said motor, an

oscillatory selector switch having an angular position approximately corresponding with the position of the car for cooperation with the respective push button switches to control the operation of said direction relays, means for automatically connecting and accelerating the motor through said low speed windings and for thereafter connecting and accelerating the motor through said high speed windings, a normally closed limit switch secured to the car and cams in the hoistway adjacent to the respective landings to open said switch when engaged thereby, electromagnetically operable means controlled by said direction relays to effect bodily movement of said switch out of alignment with said cams, said selector being adapted upon movement of the car to a predetermined point to effect disconnection of said high speed winding to provide for low speed operation of the motor, said electromagnetic means being also simultaneously deenergized to provide for movement of said limit switch into alignment with the next succeeding cam in the hoistway to provide for opening of said switch with consequent stopping of the car when the latter is accurately positioned at said predetermined landing.

In witness whereof, I have hereunto subscribed my name.

EDWIN W. SEEGER.
